(57) **CLAIM**

The ornamental design for prongs for a clip, as shown and described.

DESCRIPTION

FIG. 1 is a perspective view of the prongs for a clip.

FIG. 2 is a front view of the prongs for a clip of FIG. 1.

FIG. 3 is a back view of the prongs for a clip of FIG. 1.

FIG. 4 is a left side view of the prongs for a clip of FIG. 1.

FIG. 5 is a right side view of the prongs for a clip of FIG. 1.

FIG. 6 is a top view of the prongs for a clip of FIG. 1.

FIG. 7 is a bottom view of the prongs for a clip of FIG. 1.

FIG. 8 is a perspective view of the prongs for a clip of FIG. 1 showing a cable housed within the prongs.

FIG. 9 is a front view of the prongs for a clip of FIG. 8.

FIG. 10 is a left side view of the prongs for a clip of FIG. 8.

FIG. 11 is a perspective view of the prongs for a clip of FIG. 1 shown in an alternate environment.

FIG. 12 is a front view of the prongs for a clip of FIG. 11.

FIG. 13 is a perspective view of the prongs for a clip of FIG. 11 showing a cable housed within the prongs.

FIG. 14 is a front view of the prongs for a clip of FIG. 13.

FIG. 15 is a left side view of the prongs for a clip of FIG. 13; and,

FIG. 16 is a left side view of the prongs for a clip of FIG. 13 showing a small gauge cable housed within the prongs. The broken lines of the figures show environmental structure of the prongs for a clip and form no part of the claimed design.
